Primary Examiner — Shannon Morgan*Assistant Examiner* — Debra A Callahan(74) Attorney, Agent, or Firm — Warner Norcross + Judd LLP(57) CLAIM

The ornamental design for a makeup applicator, as shown and described.

DESCRIPTION

FIG. 1 is a perspective view of a makeup applicator;

FIG. 2 is a right side elevation view thereof;

FIG. 3 is a left end view thereof;

FIG. 4 is a left side elevation view thereof;

FIG. 5 is a right end view thereof;

FIG. 6 is a top plan view thereof; and,

FIG. 7 is a bottom plan view thereof.

The broken line show portions of the makeup applicator and form no part of the claimed design.
